UNITED STATES PATENT OFFICE.

ALPHONSE MARIE MUCHA, OF ZBIROH, AUSTRIA-HUNGARY, ASSIGNOR OF ONE-THIRD
TO THOMAS A. O'SHAUGHNESSY, OF CHICAGO, ILLINOIS.

ILLUMINATING AND PICTURE-PROJECTING APPARATUS.

1,187,443.

Specification of Letters Patent. Patented June 13, 1916.

Application filed April 1, 1913. Serial No. 758,247.

To all whom it may concern:

Be it known that I, ALPHONSE MARIE MUCHA, a subject of the Emperor of Austria-Hungary, and resident of Zbiroh, Bohemia, Austria-Hungary, have invented a new and useful Illuminating and Picture-Projecting Apparatus, of which the following is a specification.

This invention relates to means for illuminating rooms and for applying at the same time changeable mural decorations to portions of the walls or of the ceiling of the room.

A primary object is to provide simple and effective means whereby a portion of a room may be illuminated properly and whereby pictures may be projected on wall portions of the room by magic lanterns, or similar projecting devices.

Another object of the invention is to prevent interference between illuminating rays and projecting rays by interposition of screens, or similar opaque elements between the beam of light utilized for projecting and the beam of light utilized for illuminating the room.

Another object of the invention is to use one single source of light for the projection and for the illumination of the room and to dispose this source of light in a fixture which in its outer appearance does not differ from ordinary light fixtures.

The invention is illustrated in the accompanying drawing, wherein—

Figure 1 represents a sectional view through a light fixture adapted for indirect illumination of a room. Fig. 2 is a perspective view of a modified form of the subject matter of the invention. Fig. 3 is a vertical sectional view of the modification shown in Fig. 2. Fig. 4 is a view illustrated on a small scale, a vertical section of a room with the apparatus shown in Figs. 2 and 3 installed therein for illuminating and decorating purposes. Fig. 5 is a diagrammatic sectional view of a portion of a room equipped with apparatus of modified construction and arrangement for illuminating a room and for changeably decorating a portion thereof, and Fig. 6 is a plan sectional view of the room and equipment illustrated in Fig. 5.

The embodiment of the invention illustrated in Fig. 1 shows a fixture designated in general by the numeral 1. The fixture may

be secured to a portion of the ceiling by the suspension elements 2, or in some other suitable way. As it is of importance in the projection of pictures to utilize a relatively small source of light with large intensity, an arc lamp 4 is shown to be disposed within this fixture, preferably in the center portion thereof, and current is supplied to the two electrodes of the lamp by means of the conductors 3. The fixture comprises two screens 5 and 6, which are held at suitable distance and in concentric relation with respect to each other by means of the cylindrical wall 7 of the fixture, or by some other suitable means. Both of the screens are provided with central apertures 8 and 9, and the aperture of the lower screen 5 is covered by a globe-shaped member 10, which may be of opaque material so that no light emanating from the arc is used for direct illumination. This globe may also be made of translucent material so that the room receives diffused light from the arc lamp 4. When the globe 10 is used for diffusing the light part of this light will be refracted toward portions of the lower screen 5 and if this portion is of suitable lustrous appearance the light from the screen will be reflected into the room. In order to prevent that too strong a light should be thrown from the source of light 4 against the wall portions which are to receive the decorative projections the upper screen 6 is arranged at a suitable distance from the lower screen. The upper screen 6 preferably has a smaller diameter than the lower screen 5 so that the upper screen is not visible from a lower portion of the room. The light from the arc lamp will be projected through the opening 8 toward the ceiling, affording thereby what is usually termed "indirect illumination," an illumination which in many ways is preferable to direct illumination. A plurality of magic lanterns 11 are supported between the two screens 5 and 6, the tubings holding the optical equipment of the lanterns preferably extending in radial direction from the wall 7. A picture slide 12, showing the desired decoration on a relatively small scale may be interposed between the source of light 4 and the magic lanterns, the picture slides being protected from the intense heat of the arc lamp by perforated shields 13 of as

bestos or the like. When diffused light is transmitted through the globe 10 the screen 5 will cut off the rays of light passing through the globe so that the upper portion of the room is not illuminated thereby.

The modification illustrated in Figs. 2 to 4 shows a standard 17 supporting the light fixture 18 by means of the brackets 19. The standard also supports a gas pipe 10 20 through which gas or any other illuminating fuel may be conveyed to the source of light 21 shown in this instance as comprising a cluster of incandescent gas burners. The rays of light emanating from these 15 burners in downward direction are diffused through a globe 22 which is provided with a suitable perforation through which the tubing 20, holding the lamp 21, extends. In this modification the room is illuminated 20 by direct light diffused through the globe 22. In addition to the magic lanterns extending radially from the cylindrical wall 7 of this fixture a magic lantern 23 is provided which projects the decorations shown 25 on the slide 12 on the ceiling. In this modification another screen 24, surrounding the magic lantern 23, and connected with the wall 7 of the fixture prevents that light from the lamp 21 should be thrown directly on 30 the ceiling. Fig. 4 illustrates the location of a fixture of this kind with respect to a room 25. The column 17 preferably is disposed centrally within the room and the lower portion of the column rises from a plurality of settees 26. The base of the column, however, may comprise any other suitable article of use or ornamentation. It is obvious that in the modifications shown the fields of the several lanterns join to form a continuous picture. This may be varied, however, by varying the lenses in the different 40 magic lanterns, or by varying the distance of the various lens combinations to produce different focusing effects.

45 While the modifications shown above are particularly adapted for central position of the light fixture with respect to the room which is to be illuminated and decorated, in the modification shown in Figs. 5 and 6 the 50 light fixtures are arranged in niches or recesses in the vertical walls of the room so as to project pictures across the room and upon the upper portions of the opposite wall. In these figures the niches 26 only are shown and it is to be understood that a light fixture comprising a magic lantern is disposed within these niches. Screens 27 are secured to the walls 28 of the room adjacent the entrance 29 to these niches, these screens 55 serving to prevent the projecting rays from reaching lower portions of the room. The niches preferably have apertures or vents 30 through which the illuminating rays are discharged from the niches 26. These 60 illuminating rays pass through suitable

apertures 31 in the walls 32 of the room and strike the ceiling 33 thereof so that the room is illuminated indirectly.

It will be understood that this invention 70 enables variable decorative effects to be obtained, since the pictures in the lanterns may be varied at will.

The lanterns may be of any suitable construction; and, if desired, the stereopticon 75 type of lantern may be employed for enabling the decorations to be continuously varied. The combination illuminating and decorating apparatus may itself be made of very ornamental appearance; and, when skilfully constructed and arranged, the 80 illusion of permanent wall decorations by means of the picture-projecting apparatus may be readily obtained.

The foregoing detailed description has 85 been given for clearness of understanding only, and no undue limitation is to be understood therefrom. It will be understood that artistic as well as mechanical considerations will enter largely into the design of the combination apparatus, so that the apparatus 90 may take a multitude of forms.

What I regard as new, and desire to secure by Letters Patent is

1. Combination picture-projecting and illuminating apparatus, comprising a laterally directed magic-lantern, a globe beneath the plane of the magic lantern, a shield beneath the plane of the magic lantern and above the globe and beneath which the illuminating rays may pass, and means for 100 lighting the magic lantern and the globe.

2. Combination picture-projecting and illuminating apparatus, comprising a plurality of magic lanterns grouped about a vertical axis, an annular screen beneath said 105 lanterns, a depending central globe, and means for emitting light through the lanterns and globe for the purpose set forth.

3. Combination picture-projecting and illuminating apparatus comprising a plurality of magic lanterns an annular shield beneath said lanterns having an upcurved outer edge portion concealing the tubes of the lanterns from view, a depending central globe and light emitting means above the 115 globe and within the circle of lanterns.

4. Combination picture-projecting and illuminating apparatus comprising a plurality of horizontally disposed magic lanterns an annular shield beneath said lanterns, another shield above the same, and light emitting means disposed to throw projecting rays through the lanterns and illuminating rays beneath said first-named shield for the purpose set forth.

5. In an apparatus of the character described, the combination of a source of light, lantern-picture devices utilizing rays from said source of light for projecting pictures on upright wall portions of the room, and 130

frame means permitting illuminating rays to pass from said source to the ceiling of the room, thereby to illuminate said room indirectly.

5 6. A combination picture-projecting and illuminating apparatus, comprising a plurality of magic-lanterns, an annular frame supporting said lanterns and equipped with a shield below the lanterns, and light-emitting means disposed to throw projecting rays through said lanterns and illuminating rays toward the ceiling to secure indirect illumination of the room.

10 7. A combination picture-projecting and illuminating apparatus, comprising an up-

per shield and a lower shield which is of larger diameter than the upper shield, magic-lanterns disposed in the space between said shields, and light-emitting means adapted to throw projecting rays through said lanterns and to throw illuminating rays into the room outside the projection field of the lanterns. 20

In testimony whereof I affix my signature in the presence of two witnesses.

ALPHONSE MARIE MUCHA.
